G. WILLISTON.
TIN BAKER.

Patented Jan. 11, 1831.

Dec. 11. 1831

Ex. No. 1

395

Orson Williston

X 6334

Letters Patent. (Patented January 11. 1831.)

The schedule referred to in these Letters Patent and making part of the same containing a description in the words of the said Orson Williston himself of his improvement in the common Tin Baker, -

This is designed as an improvement of the common Tin Baker, now in use and has in common with that, a pan of sheet iron to contain the bread or other articles to be baked, and the whole upper part of tin, which forms such an angle with the pan as to reflect the heat from the fire before which it is placed, upon the article baked. - All these parts this Baker has in common with the bakers now in use, and I do not claim to be the inventor of the same nor of any new application of the materials composing the same. In the bakers now in use there is a top placed, (below the pan containing the bread, or other articles to be baked) to contain coals or charcoal for applying heat. The improvement consists in suspending both the pan of coals, and making the whole lower part of the baker of tin, or some other reflecting metallic surface, and the bottom pan elevated, on the back side, at such an angle as to heat the bottom of the pan, by reflection from below, in the same manner as the top is heated now, by reflection from above,

This designed that the baker should be placed before the fire, and by the heat received from the fire without coals applied above or below, effectually to bake any article placed in the pan. The benefit of this improvement are, that the baking is better performed, there being on all sides, an uniform heat and baking every part equally, that it is more convenient and economical particularly in the summer season, as a light fire kindled for a short time will be all that is necessary to bake effectually, and more safe from communicating fire, having no coals connected with them. The lower edge of the lower reflector rests upon the floor or earth, and the baker is supported on the back side, by two sheet iron legs, designed to keep it in a horizontal position.

What I claim as new, and as my invention, and nothing else

X6334

is simply the substitution of the reflecting surface in the lower part of the panel instead of the top for coils, as in the baker in common use, making thus the "Double reflecting Baker".

Dated at Norwich the 20th day of Dec. A. D. 1850.
